ERASURE SHIELD

George B. Kueter, 15103 Strathmoor, Detroit, Mich.

Filed June 8, 1959, Ser. No. 56,243

Term of patent 7 years

(Cl. D52—1)

Fig. 1.

Fig. 2.

Fig. 3.

Fig. 1 is a top plan view of an erasure shield showing my new design;

Fig. 2 is a sectional view taken on line 2—2 of Fig. 1; and

Fig. 3 is an edge elevational view thereof.

I claim:

The ornamental design for an erasure shield, as shown.
